UNITED STATES PATENT OFFICE.

JOSEF YNGVE DAHLSTRAND, OF WELLSVILLE, NEW YORK, ASSIGNOR TO STANDARD TURBINE CORPORATION, OF WELLSVILLE, NEW YORK, A CORPORATION OF NEW YORK.

STEAM TURBINE.

Application filed September 11, 1922. Serial No. 587,304.

To all whom it may concern:

Be it known that JOSEF Y. DAHLSTRAND, citizen of the United States, residing at Wellsville, in the county of Allegany and State of New York, has invented certain new and useful Improvements in Steam Turbines, of which the following is a specification, reference being had therein to the accompanying drawing.

10 The present invention relates to steam turbines of the impulse type, and more particularly to the nozzleing of steam turbines.

15 The object of this invention is to produce a steam turbine having the capability of being adjusted to suit different conditions of steam pressure and back pressure and to satisfy different power requirements.

20 Turbines of the impulse type utilize the kinetic energy of steam jets impinging on curved blades fixed to a rotor to convert the potential energy of steam under pressure into mechanical work. These jets are produced by expanding the steam in nozzles which extend at an angle to the plane of the 25 rotor and which have restricted throats communicating with the steam under pressure and mouths opening at points closely adjacent the path of the rotor blades.

25 As is well understood, in order to expand steam in a nozzle below 58% of the initial pressure, the nozzle must be divergent, that is to say, the area of the throat must be smaller than the area of the mouth. The divergence or taper of the nozzle is determined by the ratio of the admission steam pressure to the exhaust or back pressure, and the flow of steam through the nozzle is dependent upon the difference between the admission and back pressures and upon the 30 area of the throat. A turbine operating at a given speed will develop a certain number of horse power depending upon the amount of steam flowing through its nozzles. It follows, therefore, that the nozzleing of a turbine is governed by the steam conditions 35 under which the turbine is designed to operate and by the speed and horse power which it is intended that the turbine should develop.

40 According to the practice heretofore, in designing a turbine to develop a certain horse power at a given speed and under given steam conditions, the throat areas of the nozzles are calculated and then from ve-

locity and specific volumes the areas of the 55 mouths are obtained. Hence practically every turbine has been different from every other one, so far as nozzleing is concerned.

According to the present invention, a turbine is built up complete with nozzles reamed 60 straight from end to end, that is, with nozzles of uniform cross sectional area, and each nozzle is provided with means for varying its area to satisfy specific steam conditions and power requirements. The particular 65 form of nozzle contemplated by the present invention is a nozzle of circular cross section, and the particular means for varying the nozzle area is a needle valve projecting into the throat of the nozzle and protruding 70 through the turbine casing so as to be adjustable from the outside. It has been discovered that a turbine equipped with non-expanding nozzles of circular cross section 75 combined with needle valves for varying the expansion ratio can be adjusted in area to satisfy widely different steam conditions and power requirements. The present invention is based on this discovery, and effects the new result that, instead of it being necessary 80 to nozzle each turbine according to the specifications of a particular order, as heretofore, it is possible to build up and keep in stock a number of completely built turbines, one 85 or more of which can be adjusted to satisfy the requirements of an ordinary order. Obviously, this result not only simplifies the manufacturing problem and lowers the cost of production, but also involves the production of a machine of great operating flexibility.

Referring now to the accompanying drawings for a more particular description of the invention:

Figure 1 is a section on line 1—1 of Figure 95 2.

Figure 2 is a section on line 2—2 of Figure 1 and illustrates the invention applied to a single stage turbine.

Figure 3 is a view similar to Figure 2, 100 showing the application of the invention to a two stage turbine.

The present invention is not concerned with the design of a turbine as a whole, and hence the drawings are more or less fragmentary and diagrammatic. Figure 1 shows a fragment of a simple single stage turbine 105 of the two-row type. The numeral 1 design-

nates the casing in which is formed a space or ring 2 for steam under pressure and a space for accommodating the rotor. Communicating with 2 are a series of nozzles 3 through which the steam expands and thereby acquires velocity. The steam issuing from the mouths of the nozzles impinges on the rotor blades 4 and stationary blades 5, and then exhausts to the atmosphere or condenser. As indicated, the nozzles are of circular cross section and have a uniform cross-sectional area, except for the necessary rounding of the edges at the bowl. Associated with each nozzle is a needle valve 6 which has a threaded stem tapped through a hole in the casing. A cap 7 is screwed on the projecting end of the needle valve stem and is adapted to be screwed tight against the wall of a suitable recess formed in the casing. A copper-packing gasket 8 is interposed between the end of the cap and the wall of the recess to make a steam tight joint.

As stated, each nozzle of the turbine has associated with it a needle valve. All of these valves, or part of them, can be closed off entirely or else opened entirely with no part of the needle projecting in the throat of the nozzle. In the former case no steam will flow; in the latter case the maximum amount of steam will flow, and since the so-called expansion ratio would be 1:1, the nozzles would not be correct except for very low steam pressures, in other words, conditions where the back pressure exceeds 58% of the bowl pressure. Obviously the nozzles can be closed off to any desired degree between these two extremes. For example, for 80 lbs. steam pressure and atmospheric exhaust, the needle might project into the nozzle $\frac{1}{2}$ inch; for 150 lbs. pressure the needle might project 1 inch, etc. A machine equipped with nozzles and valves in accordance with this invention could be built up complete and put in stock, and it would be possible to care for any horse power and speed within the range of the maximum nozzling by opening a smaller or greater number of nozzles. Furthermore, any conditions of steam pressure and back pressure could be satisfied by the extent to which the nozzles are opened.

Figure 3 indicates the application of the invention to a multiple stage turbine. As shown, the nozzles of each stage have associated therewith needle valves, thus providing for adjustment of turbines of this type and securing correct energy and velocity distribution throughout the turbine.

Now having fully disclosed the present invention, what is claimed as new and is desired to secure by Letters Patent is:

1. In a steam turbine, the combination of a rotor having buckets thereon, a plurality of nozzles adjacent thereto, and means for varying the flow of steam through, and

for varying the ratio of the throat and tip areas of said nozzles, said means including adjustable needles projecting into the throats of the nozzles and formed to progressively increase the nozzle area from the throat to points in the nozzle substantially short of the tips thereof, whereby when the needles are moved inwardly the throat areas are decreased and increased when moved outwardly, said needles being fixed in their adjusted positions. 75

2. In a steam turbine, the combination of a rotor having buckets thereon, a plurality of nozzles of uniform circular cross section, means for varying the flow of steam through, and for varying the ratio of the throat and tip areas of, said nozzles, said means including adjustable needles projecting into the throats of the nozzles and formed to progressively increase the nozzle area from the throat to points in the nozzle substantially short of the tips thereof, whereby when the needles are moved inwardly the throat areas are decreased and increased when moved outwardly, said needles being fixed in their adjusted positions. 80 85

3. In a steam turbine, the combination of a rotor having buckets thereon, a plurality of nozzles adjacent thereto, separate means for controlling the flow of steam to each nozzle and for varying the ratio of the throat and tip areas thereof, said means including adjustable needles projecting into the throats of the nozzles and formed to progressively increase the nozzle area from the throat to points in the nozzle substantially short of the tips thereof, whereby when the needles are moved inwardly the throat areas are decreased and increased when moved outwardly, said needles being fixed in their adjusted positions. 90 95 100 105

4. In a steam turbine, the combination of a plurality of nozzles, means for controlling the flow of steam to some of the nozzles of a given stage, and for varying the ratio of the throat and tip areas thereof, said means including adjustable needles projecting into the throats of the nozzles and formed to progressively increase the nozzle area from the throat to points in the nozzle substantially short of the tips thereof, whereby when the needles are moved inwardly the throat areas are decreased and increased when moved outwardly, said needles being fixed in their adjusted positions. 110 115 120

5. In a steam turbine, the combination of a plurality of nozzles, means for controlling the flow of steam to some of the nozzles of a given stage and for varying the ratio of the throat and tip areas thereof independently of each other, said means including adjustable needles projecting into the throats of the nozzles and formed to progressively increase the nozzle area from the throat to points in the nozzle substantially short of 125 130

the tips thereof, whereby when the needles are moved inwardly the throat areas are decreased and increased when moved outwardly, said needles being fixed in their adjusted 5 positions.

6. In a steam turbine, the combination of a plurality of stages, a plurality of nozzles in one of said stages, means for controlling the flow of steam to some of the nozzles of 10 said stage and for varying the ratio of the throat and tip areas thereof, said means including adjustable needles projecting into the throats of the nozzles and formed to progressively increase the nozzle area from 15 the throat to points in the nozzle substantially short of the tips thereof, whereby when the needles are moved inwardly the throat areas are decreased and increased when moved outwardly, said needles being fixed in their 20 adjusted positions.

7. In a steam turbine, the combination of a plurality of stages, a plurality of nozzles in more than one of said stages, means for controlling the flow of steam to some of 25 the nozzles of each of said stages and for varying the ratio of the throat and tip areas thereof, said means including adjust-

able needles projecting into the throats of the nozzles and formed to progressively increase the nozzle area from the throat to 30 points in the nozzle substantially short of the tips thereof, whereby when the needles are moved inwardly the throat areas are decreased and increased when moved outwardly, said needles being fixed in their 35 adjusted positions.

8. In a steam turbine, a nozzle and an adjustable needle that is circular in cross-section, said needle being located in the nozzle axially thereof and so formed that longitudinal elements of its surface are convex 40 to the axis of the needle.

9. In a steam turbine, a nozzle that is circular in cross-section and of substantially uniform cross-sectional area throughout, 45 and an adjustable needle that is circular in cross-section, said needle being located in the nozzle axially thereof and so formed that longitudinal elements of its surface are convex 50 to the axis of the needle.

In testimony whereof I hereunto affix my signature.

JOSEF YNGVE DAHLSTRAND.
